JAR COVER

La Gardo Tackett, Los Angeles, Calif., assignor to Schmid International, a division of Schmid Kreglinger,
Inc., Boston, Mass., a corporation of Delaware

Application March 12, 1959, Serial No. 54,950

Term of patent 14 years

(Cl. D58—25)

Fig. 1 is a plan view of a jar cover showing my new design,

Fig. 2 is a side elevation of the cover with the handle in an upright position, and

Fig. 3 is a view in perspective of the cover.

I claim:

The ornamental design for a jar cover, substantially as shown.
